LABEL MOISTENING AND/OR GUMMING
DEVICE

Austin L. Voorhies, Miami, Fla.

Application January 25, 1949, Serial No. 72,690

1 Claim. (Cl. 91—51)

1

This invention relates to improvements in label moistening and/or gumming machines and has particular reference to a machine for applying moisture or adhesive to one side of a label in a novel and expeditious manner.

An object of the invention is to provide a machine for moistening gummed labels or for applying an even coating of adhesive to the back side of ungummed labels in rapid and novel manner with the labels being fed through the machine and maintained in proper contact with an applicator by a pressure device and definitely controlled during its passage against adhering to the applicator or pressure device for discharge upon a receiving bed.

A further object of the invention resides in a machine having the above named characteristics and including an applicator roller for the pick-up of moisture, adhesive or the like with a pressure roller contacting the applicator roller as a means for causing the label to evenly engage the coated surface of the applicator roller so as to avoid an uneven application of moisture or adhesive.

A further important object of the invention resides in a label moistening and/or gumming machine constructed to apply moisture to the back side of a gummed label or an adhesive to the back side of an ungummed label, with a spreader or squeegee roller contacting the side of an applicator roller, whereby heavy adhesive or the like will be spread in an even film over the applicator roller prior to its engagement by the label, thus assuring an even and complete application of the adhesive to the label.

Other important objects and advantages of the invention will be readily apparent during the course of the following description, reference being had to the accompanying drawings, wherein is illustrated a preferred embodiment of the invention.

In the drawings,

Figure 1 is a perspective view of a machine constructed in accordance with the invention.

Figure 2 is a plan view thereof, parts being broken away for sake of clearness.

Figure 3 is a vertical longitudinal section, taken on line 3—3 of Figure 2 and,

Figure 4 is a transverse vertical section taken on line 4—4 of Figure 3.

Like numerals are employed to designate like parts throughout the several figures.

Referring specifically to the drawings, the numeral 5 designates a housing, having side walls 6 and end walls 7 and 8. The side walls 6 are

inclined upwardly from the end wall 7, as at 9, and are then curved upward to a rounded extension 10. The extension 10 is then curved downwardly to merge into horizontal portions 11. The side walls 6 are provided with vertical diametrically opposite arranged slots 12 for the rotatable reception of shaft ends 13, of an applicator roller 14, to be later described. The housing 5 is provided with a horizontal depressed table 15 and a reservoir 16, both extending transversely of the housing and preferably formed integral therewith. It is contemplated that the side and end walls and the table and reservoir shall be cast as an integral unit from any suitable metal, plastic or the like. The slots 12, as plainly illustrated, are open at their upper ends to the rounded extensions 10 as a means for facilitating the removal of the roller 14.

Each side wall 6 is notched out at 17 at diametrically opposite points spaced forwardly of the slots 12. The notches 17 are provided with downward extensions 18 forming a bearing for shaft extensions 19 of a squeegee roller 20, to be described. The notches 17 provide, in addition to the extensions 18, a shelf-like surface 21 for the reception of the shafts 19 when the roller 20 is shifted to inactive position. As clearly shown in Figures 1 and 2, the shafts 19 project beyond the side wall 6 for engagement by the fingers of the operator when the roller is to be shifted.

The roller 14 extends transversely of the housing 5 and is slightly spaced at its outer ends from the inner surfaces of the side wall 6 and washers 22 are interposed between the ends of the roller and the side wall 6 for relieving frictional contact of the roller. The roller 14, see particularly Figures 3 and 4, is formed of a hollow cylindrical shell 23, closed at its ends by plates 24. One shaft 13 extends beyond one side wall 6 and carries an operating hand crank 25. While an operating crank has been illustrated as the means of rotating the roller 14, it will be apparent that other drive means may be employed such as a power pulley or the like, with equal success. The roller 14 is circumferentially grooved as at 26, at equidistantly spaced points throughout its length, for a purpose to be described. Superimposed upon and co-extensive with the roller 14 is a pressure roll, designated as a whole by the numeral 27. The roller 27 comprises a cylindrical solid shaft 28, the terminal ends of which engage in the slots 12, thus positioning the roller 27 in direct horizontal alignment with the roller 14.

The roller 27 is provided at equidistantly spaced

points throughout the major portion of its length with circumferentially arranged knife-edged ribs 29 of equal diameter and jointly bearing upon the surface of the roller 14. Hub ends 30 having a diameter equal to the ribs 29 and likewise bearing upon the surface of the roller 14 serve to limit the endwise movement of the roller 27. The diameter of the shaft 28 is substantially the same as the shaft 13. The roller 27 serves as a pressure roll for maintaining a label or the like in full contact with the surface of the roller 14 during its passage through the machine.

The roller 20, see Figure 3, when in operative position in the notched extension 16, lies parallel with and in frictional contact with the roller 14 and serves, when the device is used for applying an adhesive to labels or the like, to spread the adhesive that is picked up by the roller 14 from the reservoir 16 in an even film over the surface of the roller. When the device is used merely as a moistener for pre-gummed labels, the roller 20 is shifted to the dotted line position of Figure 3. The axial center of the roller 20 is slightly above the axis of the roller 14, for maintaining contact of the rollers.

A receiving bed for the moistened or gummed labels is indicated generally by the numerals 31 and comprises a plurality of equidistantly spaced bars 32, all fixed upon a rock shaft 33 at their rear ends and a spacer bar 34 serves to keep the several bars 32 in parallelism. The forward or free ends of the bars 32 are tapered to a point 35 and, in use the points 35 rest within the grooves 26 and thus offer no obstacle to the free and unobstructed passage of the label that has passed over the roller 14 to be projected upon the bed 31. As clearly shown, the spacing of the bars 32 is identical with the spacing of the grooves 26. The bars 32 are normally positioned above the table 15 and their upper edges are parallel with and flush with the upper edges of the side walls 6. For purposes of cleaning and dis-assembling the machine the bed 31 may be swung upwardly upon its rock shaft 33 as indicated by dotted lines in Figure 3, or may be bodily removed, since the shaft 33 is journalled in notches 33' in the side walls 6.

A cover plate 36 is arranged over the forward end of the machine and is held against displacement at its forward end by a downturned lip 37, engaging beneath a portion of the end wall 7. The forward end of the plate 36 is slotted upon opposite sides at 38 providing upwardly curved tongues 39 of a width equal to the thickness of the side wall 6 and held in direct contact with the side walls by a cap plate to be presently described. That portion of the plate 36 lying between the slots 38 is bent slightly downward to provide a label guide 40. The guide 40 extends transversely of the machine and partly overlies, but is spaced from the roller 14.

A cap plate 41 extends transversely of the machine to overlie the pressure roller 27 with its terminal ends flush with the outer surfaces of the side walls 6. The plate 41 is held in fixed position against displacement by knurled set screws 42 having engagement in threaded recesses formed in the extensions 10. The forward portion of the plate 41 is bent upon itself for providing an inwardly and downwardly extending lip 43, substantially co-extensive with the guide 40. Thus the guide 40 and lip 43 jointly provide a label directing channel that serves to direct a label over the roller 14 and beneath the roller 27. The cap plate 41 serves to prevent movement of the plate 36

by contact with the tongues 39, while the plate 36 overlies the notches 17 to prevent displacement of the roller 20. The cap plate 41 further serves to close the open end of the slots 12. Pads 44 may be employed upon the bottoms of the machine.

In the use of the device, water or adhesive is placed in the reservoir to a level below the lower ends of the slots 12. In the use of water for moistening the pre-gummed side of labels, the roller 20 is shifted to the rear of the notches 17, out of contact with the roller 14, since water will naturally form an even film. A label is then placed upon the cover plate 36, with the gummed side down and moved forwardly by the hand of the operator passing through the channel formed by the guide 40 and the lip 43. The roller 14 is revolved by the crank 25 in a clock-wise direction for picking up a film of water from the reservoir 16 and the label is moved forward until it engages between the roller 14 and the roller 27. Continued rotation of the roller 14 will carry the label thereover with its gummed side held in full contact therewith by the ribs 29 of the roller 27, imparting an even film of moisture to the back side of the label. As the label passes from between the rollers 14 and 27 it is fed outwardly upon the bed 31, where it can be conveniently removed by the operator. The sharpened ribs 29 prevent the label from adhering to and tending to follow the roller 27, as is the case with solid pressure rollers. The engagement of the pointed ends 35 of the bed in the grooves 26, presents no obstacles upon which the label might catch.

When it is desired to apply an adhesive upon unguammed labels, an adhesive solution is placed in the reservoir and the squeegee roller 20 is shifted forwardly to contact the roller 14. Since the roller 14 will tend to pick up an adhesive in uneven quantities, the roller 20 will smooth out the uneven mass and spread the adhesive in an even film over the surface of the roller 14, thus insuring of an even application of adhesive to the label. The use of the roller 20 is particularly desirable when a paste composition is employed. The multiplicity of sharpened ribs 29 is sufficient to hold the label in contact with the roller 14 throughout its travel. The rollers 20 and 27 are obviously frictionally driven from the roller 14.

The use of a pressure roller having the sharpened ribs will avoid any tendency of the label to adhere to this roller after moistening or gumming.

When it is desired to clean the machine, the cap plate 41 is removed by first removing the screws 42, after which it may be lifted off. The plate 36 may then be removed by lifting the free end and disengaging the lip 37. The bed 31 is then swung upward or entirely removed, as is desirable, since its shaft 33 is journalled in open slots formed in the side walls 6. The rollers 14, 20 and 27 may then be bodily lifted from the machine for washing or otherwise cleaning. The assembly is obviously the reverse.

While the machine has been shown and described for use in moistening or gumming labels, it will be apparent that, by the use of suitable brackets, a roll of gummed or unguammed paper may be fed through the machine where large scale sealing operations are desired. In certain conditions requiring a heavy and continuous moistening or gumming operation, it may be found desirable to substitute a pulley for the hand crank 25 and drive the machine by power means.

It will be apparent from the foregoing that a very simple and efficient machine has been designed for the moistening or gumming of labels

or the like. The parts are all simple and easily assembled and disassembled, will receive and moisten or gum a label without curling or adhering to the rollers and will project the label upon a bed where it can be easily removed. The use of the squeegee roller insures of an even film of gumming material upon the applicator roller at all times with the resulting even and complete gumming of the label against spotty and uneven gumming as would be the case without the squeegee roller. The parts are economical to manufacture, are strong, durable and highly convenient in use.

It is to be understood, that the invention is not limited to the precise arrangement shown, but that it includes within its purview, whatever changes fairly come within either the terms or the spirit of the appended claim.

Having described my invention, what I claim is:

A device of the character described for moistening gummed labels or gumming ungummed labels, comprising a rectangular housing open at its top and having side and end walls, the said housing provided with a fluid reservoir extending transversely and integral with the side walls, the side walls provided with vertical slots open at their tops, an applicator roller having shaft ends journaled in the slots, with the roller extending into the reservoir, a hand crank fixed upon one shaft end exteriorly of the housing, said roller extending transversely of the housing and having its cylindrical surface provided with a plurality of equidistantly spaced grooves, a pressure roller positioned transversely of the housing and parallel with the applicator roller, the pressure roller comprising a shaft having ends extending into the slots, said shaft provided with a plurality of equidistantly spaced and sharpened circumferential ribs, staggered with respect to the grooves and adapted to contact the surface of the applicator roller, a squeegee roller arranged transversely

of the housing and parallel with the applicator roller and having shaft ends shiftably journaled in notches formed in the side walls at diametrically opposite points and in advance of the applicator roller, with the shaft ends extending beyond the side walls, said squeegee roller when in operative position adapted to contact the side of the applicator roller by gravity for its full width and along a line slightly above the axis, the said notches extending laterally to form supports for the shaft ends when the squeegee roller is shifted to inoperative position, a cover plate and a cap plate for the housing, means carried by the plates for providing a label directing channel, a receiving bed for the moistened or gummed labels, comprising a plurality of flat bars arranged with their edges uppermost, the said bars at their rear ends fixed upon a common shaft, with the said shaft journaled in the side walls, the uppermost edges of the bars parallel with each other and with the upper edges of the side walls, the bars being equal in number and spacing to the said grooves, the forward ends of the bars being bevelled upward to a point and adapted to normally rest in the grooves with the points being below the outer surface of the applicator roller.

AUSTIN I. VOORHIES.
